GAS BURNER

Stanley H. Hobson, Rockford, Ill., assignor to Geo. D. Roper Corporation, Rockford, Ill., a corporation of Illinois

Application November 22, 1940, Serial No. 366,517

13 Claims. (Cl. 158—99)

This invention relates to gas burners and is more particularly concerned with a new and improved oven and broiler burner for gas ranges.

Efforts have been made heretofore to provide radiant burners for the reason that the effectiveness of a broiling burner depends upon its ability to produce radiant heat and direct this radiant heat toward the food being broiled. It has long been recognized that the ordinary Bunsen flame produces very small amounts of radiant heat and the only way, therefore, of obtaining the desired results is to provide radiating members which, upon being heated by the flames of the burner will emit radiant heat. It has also been realized that such radiating members would necessarily have to be of small section so as quickly to reach effective operating temperature. However, it has apparently not been realized that a radiant type burner would be practical only if the radiant members are located where they will not cause fouling of the flames. All radiant type burners with which I am familiar were objectionable because the wires or screens serving as the radiant means were located above the ports and when placed close enough to be heated red hot caused fouling, and any effort to avoid that difficulty by increasing the space relationship reduced the heating and made the wires or screens ineffective. Furthermore, the radiant screens were usually applied loosely to the burner and therefore free to shift and cause fouling. It is therefore the principal object of my invention to provide a radiant burner in which the wires constituting the radiant members, are preferably but not necessarily located below the plane of the ports and just close enough to be heated red hot, the wires being affixed between the ports so that the flow of secondary air is not obstructed and there is consequently no danger of fouling.

Another object of the invention is to provide a burner in which adjacent ports are on radial lines from a common center and are therefore in divergent relation and the wires constituting the radiant members are also radially disposed with respect to the same center, each wire being midway between adjacent ports. In that way, the wires are also in divergent relationship to the flames therebetween and although assured of being heated properly are not apt to cause fouling.

Still another object consists in providing radiant wires which although entered in holes drilled in a plane parallel to the plane of the ports are all bent upwardly at an acute angle through the plane of the ports into approximate parallelism with the general plane of the flames so that the

wires are assured of uniform heating from end to end.

A further object consists in the provision of wires the outer ends of which have enlarged spherical heads provided thereon both for improved appearance and to avoid scratching the hands of workmen in assembling or servicing the range and the housewife's in cleaning the ovens.

The invention is illustrated in the accompanying drawings, in which—

Fig. 1 is a front view of a portion of a domestic gas range with certain portions broken away to reveal the improved burner of my invention;

Fig. 2 is a plan view of the burner removed from the range;

Fig. 3 is an enlarged sectional detail on the line 3—3 of Fig. 2, and

Fig. 4 is a sectional detail on the arcuate line 4—4 of Fig. 2.

20 The same reference numerals are applied to corresponding parts throughout the views

The burner indicated generally by the numeral 5 has a double arcuate, generally oval or elliptical body 6 similarly to that disclosed in the copending application of John F. Hennessy, Serial No. 211,763, filed June 4, 1938, which resulted in Patent No. 2,253,178, issued August 19, 1941, the one

25 arcuate periphery 7 being struck from the center 8 and the other arcuate periphery 9 being struck from the center 10 and both centers being on the longitudinal center line a—b on which the mixing tube 11 also lies. The transverse center line c—d passing through the points of intersection of the arcs 7 and 9 has the burner-supporting lugs 12 and 13 lying thereon, these lugs being preferably cast integral with the body. The mixing

30 tube 11 is preferably cast separate from the burner body and suitably secured in the neck portion 14 which projects radially outwardly from the middle of the arcuate portion 9. The inner periphery 15 on the inlet side of the burner body is struck on an arc in eccentric relation to the arc 9 so that the cross-sectional area of the gas

35 passage in the burner is reduced gradually from the inlet neck 14 toward the opposite ends of the burner. In like manner, the inner periphery 16 on the side of the burner body opposite the inlet neck 14 is struck on an arc eccentric relative to the arc 7, so that the rest of the gas passage in the burner tapers gradually from the opposite ends of the burner toward the middle. In that way, the pressure at all of the ports is substantially

40 equallyized and the flames are of substantially uniform size, instead of being larger nearest the inlet neck 14 and smallest at the points most re-

mote therefrom. The gas is discharged into the burner through a mixer, as disclosed in the copending application, so that primary air is injected with the gas to form a combustible mixture burning with a Bunsen flame.

As further disclosed in said copending application, there are two series of ports 17 and 18 on the two arcuate halves of the burner body, the flames from these ports being indicated by the dotted lines at 17' and 18', respectively, in Fig. 2. The ports 17 all radiate from the point 10 and the ports 18 all radiate from the point 8. The row of ports 17 is interrupted at the neck 14. The distance between the centers of adjacent ports in both rows is the same, the distance being small enough to insure good lighting from port to port around the burner and good flame communication on turn-down. Despite this close spacing of the ports, the flames do not tend to blend near the burner into one sheet of flame and thus prevent good aeration, owing to the fact that the ports are in mutually divergent relationship, as indicated by the radial center lines 17a and 18a for the ports 17 and 18, respectively, extending from the centers 10 and 8 in Fig. 2. The gas after discharge from the ports expands and the diverging direction of the streams allows for this expansion, while at the same time permitting good access of secondary air to the individual streams. There are external peripheral ledges 19 provided by annular ribs cast integral with the body 6 of the burner above the ports 17 and 18, as clearly indicated in Figs. 3 and 4, and the gas issuing from the ports collects under the ledges to insure good communication on turn-down, so that there is no difficulty in lighting the burner. At opposite ends of the burner, on the center line c—d, are ports 20 bisecting the angles between the endmost ports 17 and 18 of the two arcuate series of ports. The flames from these ports 20 serve to light across the ends of the burner from the one row of ports 17 to the other row of ports 18, or vice versa. The end ports 20 are offset upwardly in relation to the plane of the ports 17 and 18 and the ports 20 are provided in the depressions 21 formed beneath the brackets 12 and 13, as disclosed in the copending application, the gas collecting in these depressions insuring better lighting across the ends of the burner. The ports 17 and 18 are inclined downwardly at an angle of approximately 10° from the horizontal, as indicated in Fig. 3, so that the outer ends of the ports are at a low elevation even though the bottom wall of the burner is fairly thick, and so that the inner ends of the ports are located well above the top of the bottom wall to insure easy entrance of gas thereto. Ports 22 provided along the inner periphery of the burner body 6 adjacent the inlet neck 14 are also inclined downwardly like the ports 17 and 18. These ports 22 are lighted through a slot 23 extending across the bottom of the burner to establish communication between the row of ports 17 and the row of ports 22. The center lines 22' appearing in Fig. 2 indicate the flames from these ports, which will cause sufficient air movement upwardly through the center of the burner and outwardly over the top thereof to improve aeration above the flames issuing from the ports 17 and 18, even though the burner may be set up close to an oven bottom. The ports 22 also take the place of ports omitted on the external periphery of the burner body at the inlet neck 14, whereby to insure uniform heat distribution.

In operation, the burner is lighted usually at 75

one of the pointed ends and the flame travels in both directions from the port 20 along the rows of ports 17 and 18 and finally the ports 22 are lighted by the flame propagated over the face of the burner along the slot 23. The ledges 19 aid in flame communication. Good flame communication is also attributable to the close spacing of the ports, but the close spacing does not interfere with good aeration, because the flames diverge relative to one another along radial lines from the centers 8 and 10, so that the distance between the center lines of adjacent flames increases as the flames project outwardly more and more from the burner with greater and greater turn-up. The condition never arises, therefore, where the flames blend into one sheet of flame with resultant poor combustion due to poor aeration. At each degree of turn-up, all of the flames enlarge to substantially the same size, owing to the fact that the pressure within the burner body is equalized by reason of the gradual reduction in the cross-sectional area of the gas passage away from the inlet neck 14.

The three series of wires 24, 25, and 26 constituting the radiant members are applied to the burner body 6 between the ports 17, 18 and 22, respectively, and in a plane below the plane of these ports, as indicated in Figs. 1, 3 and 4. The wires 24 and 25 are on radial lines from the centers 10 and 8, respectively, and therefore the adjacent wires of each series are in mutually divergent relation the same as the ports of the two series 17 and 18 on radial lines from the same center points 10 and 8, respectively. As clearly indicated in the drawings, the wires 24 and 25 are set in holes 27 drilled in the burner body 6 in accurately spaced relationship to the adjacent ports 17 and 18. These holes are preferably drilled in the same setup for the drilling of the ports so that there is no difficulty in locating the holes exactly midway between adjacent ports and at the desired lower elevation with respect thereto (see Figs. 3 and 4). The wires 26 are set in holes 27' the same as the wires 24 and 25, except that the holes for the wires 26 are all parallel to one another and to the ports 22, as indicated in Fig. 2. The holes 27' are, of course, below the plane of the ports 22 to the same extent as the holes 27 are below the plane of the ports 17 and 18, this lower elevation being indicated in Fig. 2 by the showing of the holes 27' in dotted outline, whereas the ports 22 are indicated in full lines in the sectioned portion. All of the wires 24, 25, and 26 are preferably pressed into the holes provided therefor and locked in place by means of a center punch, as indicated by the depression 28 in Fig. 3, the metal displaced by the center punch being sufficient to pinch the ends of the wires, as indicated at 29, and thus prevent the wires from turning or slipping out. It is important that the wires be held against turning, because of the fact that after the wires are entered in the holes they are all bent upwardly through the planes of the ports 17, 18 and 22 to the extent indicated in Fig. 3, the acute angle bend being just enough to have the wires 24, 25, and 26 lie approximately parallel to the planes of the flames from the ports 17, 18 and 22, respectively. In other words, the flames slant upwardly despite the downward inclination of the ports 17, 18 and 22, and if the wires 24, 25, and 26 were not bent upwardly to approximately the same extent, the outer ends of the wires would be spaced too far away from the flames to be heated red hot. With this relationship of the wires to

the flames, all of the wires are heated uniformly and will be red hot from end to end. The outer ends 30 of the wires 24, 25, and 26 are upset and formed between dies to the generally spherical form best illustrated in Fig. 3. This, along with having all of the wires of uniform length, makes for neater appearance and the burner has a much more attractive appearance as a result of it in operation when all of the wires are glowing, giving off radiant heat. The wires are all preferably of Inconel—a nickel steel alloy—although Nichrome wire or any other rust resistant material suitable for the present purposes might be used. I have found that No. 12 gauge wire gives most satisfactory results.

In operation, the burner 5 is disposed in a horizontal plane in the upper portion of the broiler compartment 31 under the bottom 32 of the baking oven 33, and, as is well known, the broiler pan 34 containing a suitable grill on which the meat or other food to be broiled is placed is adapted to be placed at any one of a number of elevations with respect to the burner, depending on the kind of food being broiled and the speed with which it is desired to broil it, vertically spaced ledges 35 being provided in the broiler drawer 36 to support the pan 34. The door 37 hinged on the front end of the drawer 36 and provided with a handle 38 serves as a closure for the broiler compartment 31, another door 39 being provided as a closure for the oven compartment 33. The wires 24, 25, and 26 do not interfere in any way with the operation of the burner 5, because, as previously pointed out, they are placed between the ports 11, 18, and 22 and below the same so that there is no danger of fouling. The radial divergence of the wires is just as important from the standpoint of avoiding fouling as is the radial divergence of the ports 11 and 18 from the standpoint of avoiding blending of the flames near the burner into one sheet of flame, preventing good aeration. The upward inclination of the wires 24, 25 and 26, while increasing the efficiency of heating of these wires, does not tend toward fouling because the upward inclination of the wires is not any greater than the natural upward curvature of the flames. The wires promptly after lighting of the burner become red hot and emit radiant heat, which, as is well known, has the property of penetrating and accordingly quickly heating the mass subjected to its action. The ordinary Bunsen flame produces very small amounts of radiant heat and hence the ordinary broiling burner not equipped with radiant members like the wires 24, 25 and 26 cannot be expected to broil foods nearly as efficiently. Steaks and other means can be broiled with the present burner more thoroughly in less time and are found to be juicier because of the fact that the juices do not have a sufficient opportunity of being dried out. The radiant wires 24, 25 and 26, while particularly intended to facilitate and improve the broiling operation, will, of course, improve the efficiency of the baking, roasting, and other cooking operations carried on in the oven compartment 33, especially where the pans containing such food are placed on the oven bottom 32 in sufficiently close proximity to the radiant wires to absorb the radiant heat. Where it is desired to more or less confine the effect of the radiant members 24—26 to the broiling compartment, a sheet of aluminum foil is provided, as indicated in dotted lines at 40 in Fig. 1, between the upper and lower walls of the hollow oven bottom 32, such foil having

been found to have the property of reflecting radiant heat without interfering to any appreciable extent with the heating otherwise of the oven 33 by conduction and convection.

While I have disclosed the invention as applied to a broiler burner for a domestic gas range, it should, of course, be understood that the invention is not limited to that specific application but may be applied to any gas burner on a range or elsewhere wherever the radiant heat obtained with the invention might be desirable.

It is believed the foregoing description conveys a good understanding of the objects and advantages of my invention. The appended claims have been drawn with a view to covering all legitimate modifications and adaptations.

I claim:

1. A gas burner comprising a tubular body having an arcuate wall and ports provided in said wall in equally laterally spaced relation, the ports being on radial lines from the center of the arc of said wall so that all adjacent ports are in divergent relation on small included angles, and elongated slender radiant members projecting from said wall on radial lines from the center of said arc so that all adjacent radiant members are in divergent relation on small included angles, each of said radiant members being located approximately midway between a pair of adjacent ports.
2. A gas burner as set forth in claim 1, wherein the burner body operates disposed in a substantially horizontal plane and with the adjacent ports thereof in a substantially horizontal plane, and wherein each of said radiant members is positioned in close proximity to the extended axis of an adjacent gas port and with its axis in such angular relation to said extended axis as to form a small included angle with a substantially horizontal plane that includes said extended axis whereby the member is substantially parallel with the flame from said port when operating with a full flame and whereby said radiant members are heated substantially from end to end in said flames without fouling the flames.
3. A gas burner as set forth in claim 1, wherein the burner body operates disposed in a substantially horizontal plane and with the adjacent ports thereof in a substantially horizontal plane, and wherein each of said radiant members projects from the body below the plane of the adjacent ports, but has upward inclination at an acute angle to the horizontal, for the purpose described.
4. A gas burner as set forth in claim 1, wherein the outer ends of the radiant members are of enlarged substantially spherical form.
5. A gas burner as set forth in claim 1, wherein all adjacent radiant members are of substantially equal length and have the outer ends thereof of enlarged substantially spherical form.
6. A gas burner as set forth in claim 1, wherein each of the radiant members comprises a wire of corrosion resisting metal, the body of said burner having holes provided therein in accurate spaced relation to the ports to receive the ends of said wires so as to support the same on said body.
7. In a radiant burner, a substantially horizontal burner element having spaced ports provided therein for directing flames outwardly therefrom, and a plurality of radiant members of elongated slender form to be heated by the flames and rigidly secured to the burner element so as to project outwardly from said element below but close to the ports, the burner ports having downward inclination whereby the flames projecting out-

wardly from the burner element in the operation of the burner have a predetermined upward curvature, and said radiant members being inclined upwardly at a predetermined angle relative to said ports.

8. In a radiant burner, a substantially horizontal burner element having spaced ports provided therein for directing flames outwardly therefrom, and a plurality of radiant members of elongated slender form to be heated by the flames and rigidly secured to the burner element so as to project outwardly from said element, each radiant member being positioned in close proximity to the extended axis of an adjacent gas port and with its axis in such angular relation to said extended axis as to form a small included angle with a substantially horizontal plane that includes said extended axis whereby the member is substantially parallel with the flame from said port when operating with a full flame and whereby said radiant members are heated substantially from end to end in said flames without fouling the flames, the outer ends of the radiant members being of enlarged substantially spherical form.

9. In a radiant burner, a substantially horizontal burner element having ports provided therein in a substantially horizontal plane, and elongated radiant members to be heated by the flames of the burner rigidly secured at one end to the burner element in fixed closely spaced relation to said gas ports, each radiant member being positioned in close proximity to the extended axis of an adjacent gas port and with its axis in such angular relation to said extended axis as to form a small included angle with a substantially horizontal plane that includes said extended axis whereby the member is substantially parallel with the flame from said port when operating with a full flame and whereby said radiant members are heated substantially from end to end in said flames without fouling the flames.

10. In a radiant burner, a substantially horizontal burner element having ports provided therein in a substantially horizontal plane; and elongated radiant members to be heated by the flames of the burner rigidly secured at one end to the burner element in fixed spaced relation to said ports below the same, said members projecting upwardly in a predetermined angular relation to the axes of the ports.

11. In a gas burner, a burner element having ports provided therein in laterally spaced relation in a substantially horizontal plane, the burner element having a blind hole provided therein in equally spaced relation to each two adjacent ports and closely spaced downwardly

with respect to the plane of said ports, and a rigid wire radiant member adapted to be heated by the flames from said ports set in said hole and projecting from the burner element, each radiant member being positioned in close proximity to the extended axis of an adjacent gas port and with its axis in such angular relation to said extended axis as to form a small included angle with a substantially horizontal plane that includes said extended axis whereby the member is substantially parallel with the flame from said port when operating with a full flame and whereby said radiant members are heated substantially from end to end in said flames without fouling the flames.

12. In a radiant burner, a burner element having spaced ports provided therein in a substantially horizontal plane for directing flames outwardly therefrom, and a plurality of radiant members of elongated slender form to be heated by the flames and rigidly secured to the burner element so as to project outwardly from said element, each radiant member being positioned in close proximity to the extended axis of an adjacent gas port and with its axis in such angular relation to said extended axis as to form a small included angle with a substantially horizontal plane that includes said extended axis whereby the member is substantially parallel with the flame from said port when operating with a full flame and whereby said radiant members are heated substantially from end to end in said flames without fouling the flames.

13. A radiant broiler burner comprising a substantially horizontal burner element having gas ports therein arranged in a row and in close proximity one with respect to another to provide a substantially continuous flame emanating laterally from the burner element without the inner cone of any individual flame interfering with the inner cone of the adjoining individual flames, and a row of radiant members each of elongated slender form rigidly secured to the burner element and arranged at a location intermediate two adjoining ports, each radiant member being positioned in close proximity to the extended axis of an adjacent gas port and with its axis in such angular relation to said extended axis as to form a small included angle with a substantially horizontal plane that includes said extended axis whereby the member is substantially parallel with the flame from said port when operating with a full flame and whereby said radiant members are heated substantially from end to end in said flames without fouling the flames.

STANLEY H. HOBSON.
